CANDLE HOLDER FOR BIRTHDAY CAKES

Lucille E. Scherer, Gardena, Calif.

Application November 25, 1955, Serial No. 548,905

6 Claims. (Cl. 67—25)

My invention relates to holders for the candles usually used to decorate birthday and similar decorated cakes.

Such cakes are nearly always designed to be particularly decorative, having congratulatory messages in colored icings, graceful designs of flowers, and the like, together with ruching or continuous garlands around the peripheral edge of the cake. When candle holders of the types heretofore known, which support a candle on a spike, are used it is often difficult to arrange them symmetrically without damage to the decorations and without obscuring the latter, and it is also often most difficult to position the desired number of candles on the cake without a resulting conglomeration of congested candles and holders therefor being displayed.

In general, most birthday and anniversary cakes are provided around their peripheral edges with a raised decorative border of icing, whipped cream, and the like, as well as the usual decorative designs and message displayed on the top surface of the cake; and it is the general object of my invention to provide a novel decorative holder for candles to be used in further decorating such a cake, and which holder may be firmly and securely embedded in the cake proper without likelihood of it becoming dislodged or displaced after placement on the cake, and also without contact with or damage to the decorations on the cake border; and also whereby an increased number of candles may be decoratively supported on the cake in such manner that the decorations and message on the cake top will not be obscured.

It is an object of my invention to provide a novel decorative candle holder for birthday cakes, and the like, by the use of which numerous candles may be supported on a cake while occupying only a minimum area on the top of the cake, and enabling full unobscured display of the decorations thereon.

Another object of my invention is to provide a novel candle holder of the above character, and by means of which a large number of candles may be artistically mounted on a cake with a minimum area of the cake obscured by supporting members of the holders.

A further object of my invention is to provide a novel decorative holder for candles, and by which two or more candles may be supported adjacent the edge of a cake, one candle holding socket being arranged on a portion of the supporting member depending over the side of the cake while other candle holding socket means are arranged on the supporting member above the surface of the cake, or layer thereof.

A still further object of my invention is to provide a novel decorative candle holder for birthday cakes, and the like, whereby a plurality of candle receiving sockets are supported at different levels with respect to one another on a single support that is adapted to be pushed into and embedded in the cake to be decorated.

Another object of my invention is to provide a novel decorative candle holder for birthday cakes, and the like, and in which a single support with a curved portion is

2

provided that is adapted to extend over the edge of a cake and any ruching extending around the peripheral edge of the cake, without marring said ruching, said curved portion being continued downwardly to support a candle socket adjacent the side of the cake, another portion of said supporting means serving to mount additional socket means.

Other objects, advantages and features of invention may appear from the accompanying drawing, the subject joined detail description, and the appended claims.

The accompanying drawing illustrates the invention in some of the forms I at present deem preferable.

Figure 1 is a side elevational view, partly in section, of a portion of an ornamented cake arranged in three tiers, and showing the various forms of the novel candle holders of my invention associated therewith.

Fig. 2 is a side elevational view, on enlarged scale, of one form of a novel candle holder constructed in accordance with my invention inserted into the edge of a plain frosted cake, the latter being shown in section; and a portion of the candle holding socket being shown in section.

Fig. 3 is a side elevational view of another form of a novel candle holder constructed in accordance with my invention, and arranged to hold two candles on a single supporting member; and

Fig. 4 is a side elevational view of a modification of my invention arranged to mount a single candle and provided with a supporting member adapted to be pushed into the side walls of a cake.

Referring now to Fig. 3 of the drawing, the numeral 10 indicates generally a typical embodiment of my invention which includes an elongate curved supporting member 11 having a pointed end portion 12 and an arcuate or curved portion 13 intermediate its length, a portion 14 extending generally similarly to the portion 11 and a candle holding or mounting portion 15. The socket supporting portion 15 is preferably wound in a spiral for decorative effect as shown in the drawing but obviously other forms of a decorative nature may be given to the socket supporting end 15.

The sockets 16 may be of any preferred form as shown by way of example, as being of small cylindrical blocks bored as at 20 to receive the end of birthday candles and secured to the supporting member in any suitable way.

It will be noted that by mounting one socket 16 on the high point of the curved portion 13 of the supporting member 11, and another socket 16 on the spiral end 15 which is at a lower level than portion 13, two candles may be mounted on a single supporting member 11 and give a very pleasing appearance to the cake.

The curved portion 13 is primarily provided to enable the supporting member 11 to extend over the ruching or decoration 17 usually placed around the peripheral edge of a birthday cake A and depend down the side of the cake without marring the ruching and supporting the downwardly extending portion 14 of the supporting member clear of the side of the cake which is usually covered with icing, and the curved supporting member 11 tends to "bind" the holder in mounted position on the cake A.

In the form of the candle holder shown in Fig. 2, the left hand portion 15a of the candle holder 10' is similar to that of the candle holder shown in Fig. 3 but an additional branch 18 is provided and connected in any suitable manner to supporting member 11a to extend to the side opposite to portion 15a, and may end in a similar spiral 15' on which a socket 16a is mounted at a higher level than the adjacent socket.

In the modification of the invention shown in Fig. 4, the candle holder 10", has its socket 16b mounted on

a spiral mounting portion 15b of similar form to those shown in Figs. 2 and 3 but a supporting member 11b is provided which extends laterally of, and angularly to, the mounting portion 15b to enable the candle holder 10" to be inserted in the side walls of a cake, as shown at the top in Figure 1.

The artistic and decorative effect which is achieved by the candle holders of my invention is clearly shown in Fig. 1. It will be seen that the triple candle holder shown in Fig. 2 may be used on the edge of the bottom tier 25 of a three tier cake, the double candle holder shown in Fig. 3 may be used around the edge of the second tier 26, and the single candle holder shown in Fig. 4 may be used around the sides of the top layer 27 of the cake. While candles 19 of the same height are shown in all forms of the candle holder obviously candles of various heights may be used to give different effects. The candles 19 are received in recesses 20 in the respective sockets 16, 16a and 16b.

The candle holder of my invention may be made of any suitable material as for instance of metal wire with separate receptacles to hold the base of the candles secured to the wire in any suitable manner, or the whole device may preferably be formed of plastic molded into the desired configuration.

From the foregoing, it will be seen that in the preferred form and embodiments of my invention as shown in Figs. 2 and 3, that I have provided a candle holder 10 having an elongate supporting member that is bent intermediate its ends into a substantially inverted U-shape form, one leg 11 of which is curved inwardly toward the other leg 14 thereof so as to form a more or less "hook-end" to be inserted in the cake, to thereby aid in maintaining the candle holder 10 in proper mounted position on the cake A, and the arcuate or curved portion or base 13 of said inverted U-shaped supporting member is adapted to receive, embrace or straddle the decorations 17 around the border or peripheral edge of the cake without contact therewith, or damage thereto.

The candle holders 10, 10' and 10" may be placed in staggered arrangement around the periphery of various tiers or layers 25, 26 and 27 of cake A to enhance the decorative effect of combining my novel candle holders with birthday cakes, and the like.

While certain specific embodiments of my invention have been herein described and shown in the drawing, it will be obvious that various modifications may be made by those skilled in the art without departing from the scope of the invention as defined in the appended claims.

I claim:

1. A candle holder for cakes, and the like, including an inverted U-shaped supporting member, one leg of which member is adapted to be inserted into a cake and receive the peripheral edge of a cake within the curved base portion of said inverted U-shaped supporting member; and a plurality of candle receiving and retaining members connected to and supported by said U-shaped

supporting member, and one of said candle receiving members being located at one end of said U-shaped member.

2. A candle holder for cakes, and the like, including an inverted U-shaped supporting member, one leg of which member is adapted to be inserted into a cake and receive the peripheral edge of a cake within the curved base portion of said inverted U-shaped supporting member; and a plurality of candle receiving and retaining

10 members connected to and supported by said U-shaped supporting member, said first-mentioned leg member being curved inwardly toward the other leg member, and one of said candle receiving members being located at one end of said U-shaped member.

15 3. A candle holder for cakes, and the like, including an inverted U-shaped supporting member, one leg of which member is adapted to be inserted into the top of a cake and receive the peripheral edge of a cake within the curved base portion of said inverted U-shaped sup-

20 porting member, and the other leg of said supporting member being adapted to extend downwardly adjacent the side wall of the cake; and a plurality of candle receiving and retaining members connected to and sup-

25 ported by said U-shaped supporting member, said first-mentioned leg member being curved inwardly toward the other leg member; and said candle receiving members being positioned to support a candle in each thereof at different levels relative to the cake top, and one of said candle receiving members being positioned to support a

30 candle from the free end of said other leg member.

4. A candle holder for cakes, and the like, comprising a supporting member that includes a generally vertical portion for insertion into the top of a cake adjacent the peripheral edge thereof, a curved portion adapted to

35 extend above and over the peripheral edge of the cake, and a downwardly extending portion depending from the curved portion and adjacent the side wall of the cake; and a candle receiving socket respectively secured to said curved portion and another candle receiving socket

40 secured to said downwardly extending portion.

5. A candle holder as defined in claim 4, and in addition comprising an additional supporting member ex-

45 tends from said generally vertical portion and above

the top of the cake; and another candle receiving socket

45 secured to said additional supporting member.

6. A candle holder as defined in claim 4, and in addi-

tion the generally vertical portion being curved inwardly

toward the downwardly extending portion of said sup-

porting member.
